UNITED STATES PATENT OFFICE.

FREDERIK LANDENBERGER, OF NEW YORK, N. Y.

DESIGN FOR A POMPON.

SPECIFICATION forming part of Design No. 14,326, dated September 25, 1883.

Application filed August 4, 1883. Term of patent 3½ years.

To all whom it may concern:

Be it known that I, FREDERIK LANDENBERGER, a citizen of the United States, residing in the city, county, and State of New York, have invented and produced a new and original Design for a Chenille Pompon, of which the following is a specification, reference being had to the accompanying photographic illustration, forming part therof.

10 Figure 1 is a front elevation of my newly-designed pompon; and Fig. 2 is a front elevation, showing a slight modification of the form of the tufts of which the pompon is composed.

15 The leading feature of my design consists of a ball or pompon composed of short pieces held together in a bunch, the ends of the tufts standing out radially all over the ball or pompon.

20 Another feature of the design consists in making the tufts composing the pompon of small diameter at their outer ends.

a represents the short pieces or tufts composing my newly-designed pompon. A great

number of these tufts or short pieces *a* are to form a globe or ball, the tufts standing out in 25 radial position with reference to the center of the cluster, and these tufts *a* are made conical or of small diameter at their outer ends, as shown, so that the cluster as a whole will present to the eye the effect of a cluster of tufted 30 cones resembling the capitulum of a flower.

I claim—

1. The design for a ball or pompon herein shown and described, consisting of a cluster of short pieces or tufts standing out radially 35 to the cluster.

2. The design for a ball or pompon herein shown and described, consisting of a cluster of short pieces held in ball form, the tufts being of small diameter at their outer ends, and 40 held in radial position with reference to the cluster.

FREDERIK LANDENBERGER.
